United States Patent Office

Des. 232,201

Patented July 30, 1974

232,201

MAGAZINE RACK

Morton Hoffman, West Hempstead, N.Y., assignor to
Select Magazines, Inc., New York, N.Y.

Filed Oct. 2, 1972, Ser. No. 294,234

Term of patent 14 years

Int. Cl. D6—04

U.S. Cl. D6—114

FIG. 1.

FIG. 2.

FIG. 3.

FIG. 4.

FIG. 5.

FIG. 6.

FIG. 7.

FIG. 1 is a perspective view of a magazine rack showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

I claim:

The ornamental design for a magazine rack, substantially as shown.
